FIG.4

FIG.5

FIG.6

FIG. 1 is a side elevational view of the sailboat with an indication by a line underneath of the various points at which the half sections of FIG. 6 are taken.

FIG. 2 is a top plan view of FIG. 1 with the sail and mast omitted for clarity.

FIG. 3 is a cross-sectional view taken along line 3—3 of FIG. 2, with part of the centerboard omitted for ease of illustration.

FIG. 4 is an elevational view from the stern with the sails and mast omitted for ease of illustration.

FIG. 5 is an elevational view from the bow with the sails and mast omitted for ease of illustration.

FIG. 6 shows hull half sections as traditionally prepared by naval architects with the station numbers corresponding to the numbers of FIG. 1.

The port side of the boat is substantially identical in appearance to the starboard side shown in FIG. 1.

What is claimed is:

The ornamental design for a sailboat, substantially as shown and described.
